(57) CLAIM

The ornamental design for a “writing instrument,” as shown and described.

DESCRIPTION

FIG. 1 is a perspective view of a writing instrument embodying my new design;

FIG. 2 is a front elevational view of the writing instrument of FIG. 1;

FIG. 3 is a right side elevational view of the writing instrument of FIG. 1, the left side elevational view being a mirror image thereof;

FIG. 4 is a rear elevational view of the writing instrument of FIG. 1;

FIG. 5 is a bottom plan view of the writing instrument of FIG. 1; and,

FIG. 6 is a top plan view of the writing instrument of FIG. 1.

1 Claim, 2 Drawing Sheets
